FIG. 4.

By *Alanson L. Scott*
Attorneys

UNITED STATES PATENT OFFICE.

CHARLES A. SCOTT, OF ROCKFORD, ILLINOIS.

CALCULATING MACHINE.

Application filed August 7, 1924. Serial No. 730,666.

To all whom it may concern:

Be it known that I, CHARLES A. SCOTT, a citizen of the United States, residing at Rockford, in the county of Winnebago and State of Illinois, have invented certain new and useful Improvements in Calculating Machines; and I do declare the following to be a full, clear, and exact description of the invention, such as will enable others skilled in the art to which it appertains to make and use the same.

My invention relates to improvements in calculating machines of the type having a plurality of numeral wheels bearing the numerals 1 to 9 and zero, together with setting racks for the wheels, usually operated by means of an ordinary pencil or like device. The numeral wheels in the present disclosure are provided with gears with which the teeth of the racks mesh; means are provided for temporarily holding said racks in any of the numerous positions to which they may be moved, and upon release of such means, the racks return to their normal positions. One object of the invention is to provide novel means for first relatively moving said racks and wheels to entirely unmesh the gears from the racks, and for then releasing the rack-holding means, insuring that return movement of the racks and any recoil which might take place, shall not change the settings of the numeral wheels.

In the preferred form of construction, the numeral wheels are movable away from the racks, and a further aim is to provide a novel carrier for said wheels and unique operating means for moving said carrier in a manner to effect unmeshing of the numeral wheel gears and racks.

A further aim is to provide a construction in which part of the carrier-operating means serves to release the rack-holding means after the gears and racks have been moved out of mesh with each other.

In machines of the class to which I have referred, when any numeral wheel of a relatively low denomination is turned beyond a given point (at which 9 is visible), it is often necessary that the next turning of said wheel shall advance the numeral wheel of the next higher denomination one step. It is a further object of the invention to make novel provision for effecting this result.

A still further object is to provide a struc-

ture in which part of the means for moving the above named wheel-carrier forms part of the means for advancing a wheel of a relatively high denomination by means of the wheel of the next lower denomination, as referred to in the preceding paragraph.

Yet another aim is to provide resetting means for the numeral wheels, into engagement with which said wheels are moved, when shifted away from the setting racks.

An additional object is to provide a calculating machine which will be extremely simple and inexpensive, easy to operate, accurate, durable, fool-proof and in every way desirable.

With the foregoing and minor objects in view, the invention resides in the novel subject matter hereinafter described and claimed, the description being supplemented by the accompanying drawings.

Figure 1 is a top plan view of a calculating machine constructed in accordance with the invention.

Figure 2 is a bottom plan view with the casing bottom removed.

Figure 3 is a longitudinal sectional view on line 3—3 of Fig. 2, illustrating one of the setting racks held in a position to which it has been moved.

Figure 4 is a view similar to Fig. 3 showing the manner in which the numeral wheel gears are unmeshed from the setting racks before release of the rack-holding means.

Figure 5 is a view similar to Figs. 3 and 4 illustrating the way in which a relatively low denomination numeral wheel advances the wheel of the next higher denomination. In this view, the first setting rack is omitted.

Figure 6 is a perspective view of the numeral wheel carrier.

Figure 7 is a perspective view of the flanged bar which is secured on the carrier for engagement with levers which operate the carrier and perform other functions hereinafter described.

Figure 8 is a perspective view of one of the levers referred to in the preceding paragraph and one of the rack-actuating levers.

Figure 9 is a detail sectional view of a different means for operating the resetting roller.

In the drawings above briefly described, the numeral 1 designates an elongated casing which may be described as having a top plate 2, although the device may be used

in such a position that the plate 2 would constitute more of a front plate than a top plate. For clearness of explanation however, the device will be hereinafter described as if it were used in a horizontal position.

The top plate 2 is formed with a plurality of parallel longitudinal slots 3 and with an equal plurality of view openings 4. 10 Visible through these openings, are the numerals of a plurality of numeral wheels 5 of gradually increasing denominations, each wheel being provided with the numerals 1, 2, 3, 4, 5, 6, 7, 8, 9 and 0. All 15 of the wheels 5 are frictionally mounted upon a transverse shaft 6 in axial alignment with each other, and each wheel is provided with a spur gear 7. These gears mesh with the teeth 8 of setting racks 9 which are slidably engaged with the slots 3 and provided with springs 10 by means of which they may be returned to normal position, in which position they abut against a stop 11 extending across the top of the 20 plate 2. Each of the setting racks 9 is provided with a plurality of sockets 12 which are numbered from 1 to 9. The point of a pencil or the like may be inserted in any of these sockets and the desired rack 9 thus 25 moved until the pencil or other manipulating device comes in contact with a stop bar 13 which extends across the top of the plate 2. This manipulation of the rack, causes the numeral wheel 5 associated with said 30 rack to display a number in the adjacent opening 4 corresponding to the number of the socket into which the pencil or the like is inserted. This general manner of 35 operation is common to a number of devices similar to my invention and requires no 40 further explanation.

A plurality of self-applying dogs 14 have been shown in the casing 1, positioned to engage the teeth 8 of the racks 9 so as to 45 hold said racks temporarily in any positions to which they may be moved. It is intended however, that after operation of any of the racks 9, the gears 7 shall be moved out of mesh with the racks, and the dogs 14 then released, so that the rack or 50 racks previously operated may return to their normal positions under the influence of the springs 10. To accomplish these results, a novel construction and arrangement 55 of parts is provided.

A carrier is provided for the shaft 6. This carrier preferably comprises a pair of parallel side arms 15 which carry the shaft 6 upon which the wheels 5 are mounted. The 60 arms 15 are held in spaced relation by a transverse flat bar 16 and a tie-rod 17, in the present disclosure, and these arms are pivoted to the side walls of the casing by a transverse rod 18. An appropriate spring 65 19 is provided to normally swing the entire

carrier toward the racks 9, so as to hold the gears 7 in mesh with the rack teeth 8, but means are provided for swinging said carrier to unmesh the gears from the rack teeth and to then release the dogs 14.

70 A transverse bar or plate 20 is shown, suitably secured upon the bar 16, said bar 20 having parallel lateral flanges 21 and 22, the former also having a flange 23 which extends toward the flange 22. This flange 22 is formed with a plurality of slots 24, for a purpose to appear.

Extending transversely of the shaft 6 and the bar 20 are a number of levers 25 whose intermediate portions are slidably received 80 in the slots 24 and are provided with fingers 26 interposed between the flange 23 and the bar 20 to engage the former. These levers are fulcrumed at one end as indicated at 85 27 and at their other ends, they are provided with lugs 28 which overlie and are normally spaced above the dogs 14. These lugs 28 are instrumental in releasing the dogs 14 of all units of the machine, except the unit of the lowest denomination. The dog 90 of this unit however is released by means hereinafter described.

A lever-operating plate 29 extends transversely of the casing 1 and is pivoted therein at 30, said plate having arms 31 which overlie the lugs 28 as seen in Figs. 3 and 4. The plate 29 is also provided with an operating arm 32 to which a push rod 33 is connected, said rod extending to the exterior of the casing, at one end of the latter. 100 When this push rod is forced inwardly, plate 29 is rocked about its pivot 30, causing the arms 31 to engage the lugs 28 and swing the levers 25 downwardly, causing the fingers 26 to pull downwardly upon the flange 23, thereby swinging the carrier arms 105 15 downwardly and moving the gears 7 out of mesh with the rack teeth 8. One or more of the racks is then held in the position to which it has been previously moved by 110 one or more of the dogs 14. As soon as the gears 7 are out of mesh with the rack teeth 8, the lugs 28 release the dogs 14 from engagement with said rack teeth, thereby releasing the rack or racks and permitting 115 return to normal position. When this return takes place, the gears and racks are entirely out of mesh so that there is no danger whatever of any return motion on the part of the racks, or any recoil, effecting any movement whatever of the numeral 120 wheels 5.

I have stated above that the dog 14 of the rack 9 for the numeral wheel having the lowest denomination, is not released by one of the lugs 28. In the present showing, to accomplish this function, a lug 34 is provided on one of the arms 31.

125 The fulcrums 27 for the levers 25 are carried by the lower ends of a plurality of 130

- angular actuating levers 35 which are provided for all of the setting racks 8, except the rack for the numeral wheel of the lowest denomination. These actuating levers are so disposed that when the racks 9 are in their normal positions, they engage the levers as shown in Fig. 3. At certain times, one or more of the levers 35 are operated from certain of the numeral wheels 5, through the instrumentality of lateral pins 36 on said wheels, engageable with shoulders 37 on the levers 25, and when any of said levers 35 is moved by its respective lever 25, it in turn moves the setting rack 9 with which it contacts, so as to turn the numeral wheel 5 associated with this rack, the distance between two numerals of said wheel, that is one step of a revolution.
- 20 By the association of parts just described, it will be seen that when any wheel 5 of a relatively low denomination has been turned until its pin 36 contacts with the co-acting shoulder 37, that the next operation of said wheel will cause said pin and shoulder to longitudinally shift the associated lever 25, causing said lever to in turn move the lever 35 with which it is connected, thereby operating the setting rack 9 for the wheel 5 of the next higher denomination. For instance, if two of the wheels 5 should be set so as to disclose 69 in the openings 4, and the setting rack of the wheel displaying 9 is moved to add 35 the numeral 1, such movement of the rack will move the wheel to display a zero instead of a 9, and this movement of the wheel causes turning of the next adjacent wheel to show 7 instead of 6.
- 40 Before proceeding, the facts may be emphasized that the levers 25 form part of the means for swinging the wheel carrier away from the setting racks 9, that said levers 25 also form part of the mechanical actuating means for said setting racks, and that the levers in question further act as releasing means for the dogs 14. The elimination of a number of parts has thus been effected by assigning a multiple function to the levers 25.
- 45 Means are provided associated in a novel manner with the parts above described, for re-setting the numeral wheels 5 at the end of any calculating operation. At 38, I have shown a re-setting roller extending across the casing 1 and provided with a number of rubber faces or the like 39, into contact with which the wheels 5 may be moved by manipulation of the push rod 33 to swing the carrier arms 15 and said wheels away from the setting racks 9. Thus, by turning the roller 38, all of the wheels 5 may be reset, so that their zeros appear in the openings 4, the re-setting movement of the wheels being limited by suitable stops 40 on a cross bar 41, which stops co-act with the pins 36 above described. Any desired means may be employed for turning the roller 38, such as the knob 42 shown in Fig. 2, or the rack 43 and ratchet 44 depicted in Fig. 9.
- 50 In operating the device, the wheels 5 are set by manipulation of the setting racks 9 and each rack is momentarily held in the position to which it has been moved, by the dog 14. After each operation of the racks, the push rod 33 is operated, causing unmeshing of the gears 7 from the ratchet teeth 8 and permitting return of the racks to their normal positions, and often when any of the numeral wheels is turned beyond the point at which its numeral 9 is visible, said wheel operates the associated levers 25 and 35 to move the rack 9 for the wheel of the next higher denomination, turning the latter one step. At the completion of any calculating operation, the push rod 33 is used to shift the wheels 5 into contact with the re-setting roller 38, so that this roller may be used to re-set all of the wheels at zero, leaving the device in readiness for another calculation.
- 55 Excellent results have been obtained from the general construction shown and described and such construction is therefore preferably followed, but within the scope of the invention as claimed, numerous modifications may be made.
- I claim:
1. A calculating machine comprising a numeral wheel having a gear, a slidable setting rack meshing with said gear, means for holding said rack in any position to which it is moved, and means for first moving said rack and gears relatively to entirely unmesh them and for then releasing said rack-holding means.
  2. A calculating machine comprising a numeral wheel having a gear, a slidable setting rack meshing with said gear, means for holding said rack in any position to which it is moved, a carrier for said numeral wheel mounted for movement away from said setting rack, and means for first moving said carrier to entirely unmesh the gear from the rack and for then releasing said rack-holding means.
  3. A calculating machine comprising a numeral wheel having a gear, a slidable setting rack meshing with said gear, means for holding said rack in any position to which it is moved, a movably mounted carrier on which said wheel is mounted, and a lever connected with said carrier for moving it away from the rack to unmesh the gear from said rack, said lever having means for releasing said rack-holding means after it is moved to gear and rack-unmeshing position.
  4. A calculating machine comprising a support, a numeral wheel under said sup-

4-
10
15

port having a gear, a setting rack slidably engaged with said support and meshing with said gear, means under said support adapted to engage said rack and hold it in any position to which it is moved, a carrier for said wheel movable downwardly from said support, a lever mounted under said support and adapted to move said carrier downwardly to unmash the aforesaid gear from the setting rack, said lever having a lateral lug engaged with said rack-holding means to release the latter when the gear and rack have been unmashed, and a manually controlled actuator for said lever.

5. A calculating machine comprising a numeral wheel having a gear, a slidably mounted setting rack meshing with said gear, means adapted to engage said rack and hold it in any position to which it is moved, 20 a pair of parallel arms pivotally mounted for movement toward and from the rack, said wheel being carried by said arms, a cross bar secured at its ends to said arms, a lever having a portion engaging said cross bar to swing the arms and unmash the aforesaid gear from the rack, said lever engaging said rack-holding means to release the latter after unmashing of the gear from the rack, and a manually-controlled actuator for the lever.

6. A calculating machine comprising numeral wheels of relatively low and high denominations, separate setting devices for said wheels, a carrier on which said wheels 35 are mounted, means for moving said carrier to move said wheels out of operative relation with said setting devices, and transfer mechanism formed in part by a portion of said carriage moving means.

40 7. A calculating machine comprising a numeral wheel of relatively low denomination, a second numeral wheel of comparatively high denomination, separate setting devices for said wheels, a carrier for said wheels adapted to move them out of operative engagement with said setting devices,

an actuating member for the setting device of the high denomination wheel adapted to be engaged by such device when the latter is in its normal position, a lever connected to said actuating member and connected also to said carrier, means for swinging said lever to move the carrier and thereby shift the numeral wheels out of operative engagement with the setting devices, and means for bodily shifting said lever to operate said actuating member when said low denomination wheel is turned beyond a predetermined point.

8. A structure as specified in claim 7; 60 said actuating member having a finger slidably engaged with said carrier to establish connection between the two.

9. A calculating machine comprising a numeral wheel of relatively low denomination, a second wheel of comparatively high denomination, a carrier for said wheels, said carrier being provided with a cross bar having parallel lateral flanges and a third flange extending from one of said pair of flanges to the other flange, said other flange having a transverse slot, separate setting devices for said wheels adapted to return to initial position when the wheels are moved out of operative relation therewith, an actuating lever for the setting device of the high denomination wheel, a second lever connected at one end to said actuating lever and having a finger passing through the above named slot and slidably engaging said third flange, means for swinging said second lever to move the aforesaid carrier and consequently shift the numeral wheels out of operative relation with the setting devices, and means for longitudinally shifting said second lever to operate the above-named actuating lever when the low denomination wheel is turned beyond a predetermined point.

In testimony whereof I have hereunto 90 affixed my signature.

CHARLES A. SCOTT.
